MARTIN RASMUSSEN, OF RACINE, WISCONSIN, ASSIGNOR TO HARTMANN TRUNK COMPANY, OF RACINE, WISCONSIN, A CORPORATION OF WISCONSIN.

TRUNK LOCK.

Application filed July 7, 1923. Serial No. 650,186.

This invention relates to wardrobe trunks and particularly to drawer locking means for trunks of this character.

Wardrobe trunks now in extensive commercial use are ordinarily provided with a plurality of drawers and are furthermore provided with locking bars designed to lock in closed position all of the drawers. This invention relates particularly to the lock 10 carried by this locking bar.

This invention has for its object to simplify and improve locking device of this character, and to this end this invention consists in the novel combination, construction 15 and arrangement of parts all as will be made more apparent hereinafter as the description proceeds, especially when considered in connection with the accompanying drawings wherein:

20 Figure 1 is an elevational view of a portion of a wardrobe trunk containing the drawers and illustrating a locking bar having associated therewith this improved lock;

Fig. 2 is a fragmentary elevational view 25 of the locking bar showing the lock;

Fig. 3 is a detailed view, showing the interior construction of the lock;

Fig. 4 is a similar view with the bars in 30 unlocked position;

Fig. 5 is a central longitudinal sectional view on the plane indicated by the line 5—5 in Fig. 3;

Fig. 6 is a transverse sectional view; and,

Fig. 7 is a detailed view of the locking 35 discs.

Referring now particularly to the drawings wherein like reference characters indicate like parts, it will be noted that a portion of a wardrobe trunk 10 is illustrated, 40 having mounted therein a plurality of drawers 11. These drawers are secured in closed position by means of a locking bar 12, hooked at its lower end into a slotted plate 13, secured to the trunk and engaging intermediate its length an open ended slot, formed 45 in a plate 14, also secured to the trunk. The bar is preferably hinged as at 15 intermediate its length.

The bar 12 has secured at its upper end 50 a lock enclosed in a casing 16, there being

contained in this casing a pair of locking levers 17, pivoted as at 18 and normally urged outwardly to the position illustrated in Fig. 3, by means of an U-shaped spring 19. In this position the angularly extending locking projections 20 of the levers 17 engage keepers 21, forming a part of the escutcheon plate of the trunk to securely lock the bar 12 thereto.

A cam member 22, forming a part of the locking mechanism is rotatably supported within the casing 16 between the lower ends of the locking levers 17, and when rotated tends to move these levers to unlocking position, as illustrated in Fig. 4. This cam member 22 is rotated by a key 23, adapted to be inserted in a rotatable key-receiving member 24. This rotatable key-receiving member extends through a plurality of locking or ward discs 25, non-rotatably supported 70 within the casing upon pins 26. These discs are provided centrally thereof with openings 27, communicating with slots 28.

The openings 27 are of different diameters, and the key 23 insertable therethrough must 75 therefore be formed with suitable dimensioned slots to permit its rotation with reference to the discs 25. The key-receiving member 24 engages the cam 22 in such a manner as to rotate the same when the key 80 insertable in the member 24 is rotated. Obviously, therefore, when the proper key is inserted in the key-receiving member 24 the key and the member 24 may be rotated relatively to the discs 25 and in consequence 85 thereof the cam 22 will be rotated from the position illustrated in Fig. 3 to that illustrated in Fig. 4, whereupon the locking levers 17 will be moved to unlocked position against the tension of the spring 19. It 90 will be also immediately apparent that various combinations may be provided by altering the arrangement of the discs 25, thus necessitating keys of different formations.

While one embodiment of the invention 95 has been described herein in some detail, it is not intended that the invention be unnecessarily limited, but reservation is made to make such changes as may come within the purview of the accompanying claim. 100

Having thus described the invention what is claimed is:

A lock comprising a casing, a pair of locking levers pivotally mounted therein, a rotatable cam for moving said locking levers to unlocked position, a plurality of locking discs non-rotatably mounted within said casing and provided with apertures of different

diameters and a key-receiving member passing through said locking discs and engaging said cam, said key-receiving member being rotatable upon the insertion of a proper key to rotate said cam.

In testimony whereof, I affix my signature.

MARTIN RASMUSSEN.
